UNITED STATES PATENT OFFICE

2,302,727

METHOD OF MAKING YARN GUIDE TUBES

August L. Weisbecker, Roslyn, Pa., assignor to
Hosiery Patents Incorporated, Lansdale, Pa., a
corporation of Pennsylvania

Application February 27, 1940, Serial No. 321,130

16 Claims. (Cl. 29—170)

This invention relates to a method of making yarn guide tubes, and more particularly to methods of making yarn guide tubes for use on straight knitting machines.

The invention will be described with regard to straight knitting machine yarn guide tubes, and its application in the making of yarn guide tubes for other types of machines will be understood from the following disclosure.

In the art of knitting machines, such as the straight knitting machines used for the manufacture of full fashioned hosiery, it is now the practice to feed yarn to the knitting needles by means of yarn carriers such as shown in the patents to Frank G. Weisbecker, Nos. 2,014,341, dated September 10, 1935; 2,026,514, dated December 31, 1935; and 2,101,801, dated December 7, 1937. These patents also show yarn guide tubes which are at least in part of flexible construction to avoid damage to parts of the knitting machine should the guide tubes accidentally strike misplaced sinkers or other obstructions during knitting operations. The present invention has application to this type of yarn guide tube shown in the noted Weisbecker patents.

As illustrated in the earlier two of the three above-noted Weisbecker patents, the yarn 7 in passing from the yarn guide tube is fed at a substantial angle relative to the axis of the tube. The yarn, therefore, tends to exert a cutting action on the yarn guide tube tip as the former passes over the tip edge. This cutting action is quite pronounced where the yarn is formed of natural silk, and is much more pronounced where the yarn is made of the artificial material which has been lately developed and proposed for use in the making of knitted hosiery.

Prior to the filing of this application, it has been proposed to provide yarn guide tubes with tips of special materials which are wear resistant. Such proposal is to form the yarn guide tips from tubular stock which has been produced in a drawing operation. That practice has limited the choice of materials which may be used in forming the yarn guide tips, as it is difficult, impractical, or impossible to draw a number of highly desirable wear resisting materials into tubular form. This invention overcomes the described limitations in the art and teaches a method whereby an unlimited number of materials may be used for yarn guide tips. At the same time, the invention secures a yarn guide of highly desired characteristics.

It is, therefore, an object of this invention

to provide a novel method for making an improved yarn guide tube.

It is a further object of this invention to provide yarn guide tubes with novel tips formed of materials which are highly wear resistant to the cutting action of yarn or thread whether natural silk, artificial yarn or other material.

A still further object is to provide a yarn guide tube especially adapted to the needs of the newer artificial yarns for full fashioned hosiery.

It is a further object of this invention to provide a novel yarn guide tube which is characterized both by its flexibility and by the highly wear resistant properties of its yarn feeding tip.

Still another object is to provide a novel method for providing yarn guide tubes with wear resisting tips.

Other objects and advantages of this invention will be obvious from the following description, the appended claims, and the attached drawing which illustrate preferred embodiments of this invention.

Referring to the drawing,

Figure I is a perspective view of a straight knitting machine yarn carrier having a yarn guide tube formed in accordance with this invention.

Figure II is an elevational view on enlarged scale of the lower end of the yarn carrier of Figure I.

Figure III is a sectional view of the members which are formed into a yarn guide tube as shown in Figures I and II.

Figure IV is an exploded view of the parts from which a yarn guide tube is formed in accordance with this invention.

Figures V—VIII inclusive are longitudinal, cross sectional views and illustrate the successive steps in the forming of a yarn guide tube in accordance with a preferred embodiment of this invention.

Figure IX is a diagrammatic view to illustrate another embodiment of the present method for forming yarn guide tubes.

Coming now to a description of the accompanying drawing and an explanation of the present invention, the yarn carrier in Figure I comprises a yarn guide tube supporting arm, or yarn carrier arm, 10 and a yarn guide tube 11. The yarn guide tube 11 may be removably supported in the lower end of the supporting arm 10, as more clearly shown in Figure II. The supporting means for the yarn guide tube 11 may comprise two branches 12 and 13 which are preferably welded at lines 14 to the upper portion of supporting arm 10 in any suitable manner. The

branches 12 and 13 are provided with jaws 15 and 16 which provide a socket for and grip the side walls of the yarn guide tube 11. Shoulder 17 provides an abutting surface for the inner end of the yarn guide tube 11 and constitutes the bottom of the socket for the same. The jaw 15 is relatively rigidly supported by its branch 12. The jaw 16, however, is resiliently supported by the arm 18 of the branch 13. The arm 18 may be formed by providing a slot 19 in the branch 13 which is preferably of such material as to provide the desired resiliency in the arm 18. The resilient arm 18 extends from the jaw 16 in a direction outwardly thereof and toward the lower end of the yarn carrier. The arm 18 will, therefore, support jaw 16 so that it resists axial movement of the tube 11, in the direction to withdraw the same from its socket, with substantially greater force than it does axial movement of the tube 11 in the direction to insert the same into its socket.

The yarn guide tube 11 of this invention may be formed from a tubular member 25 and two disk-like blanks or elements 26 and 27. The tubular member 25 is preferably of flexible construction, and may comprise, for example, a resilient, helical coil spring formed of both metallic ribbon (flat wire) and wire of round cross section as described in above-noted Weisbecker Patent No. 2,101,801 and illustrated in Figure V of the same patent. The thickness of the metallic ribbon is preferably the same as the diameter of the round wire so as to provide the tubular member 25 with substantially the same wall thickness throughout its length.

The disk-like elements 26 and 27 are preferably formed of a metallic material, which may be heat treated, and which is highly wear resistant and substantially more wear resistant than the tubular member 25 to the cutting action of thread or yarn, whether of natural silk, artificial yarn or other material. Suitable materials for the disk-like elements 26 and 27 are tungsten and heat treatable alloys of a character which permits them to be cut and smoothed in a machine operation. The disk-like elements 26 and 27 may be formed of plain carbon steels having a carbon content of about .05 per cent to about 1.05 per cent carbon. Other suitable materials are chromium steel alloys having a chromium content ranging for example from about 6 per cent to about 13 per cent and a carbon content ranging for example from about 1.25 per cent to about 2.50 per cent.

Experience shows that it is difficult, impractical, or impossible to draw a number of desirable materials into tubular form, particularly of the size required for yarn guide tubes. Tungsten is an example of such materials. Metals on the order of tungsten, if they are subjected to die drawing, have such characteristics that they soon wear out the dies in the drawing operation. It is also considered impractical to draw chromium steel alloys having a carbon content of about 1.25 per cent to about 2.30 per cent into tubular form as they tend to become hard under the slightest amount of work or deformation of the metal.

The disk-like elements 26 and 27 may be cut from imperforate stock having the desired thickness for the tips of the yarn guide tubes 11. Where the yarn guide tubular member 25 is provided with one end smaller than the other as described hereinafter and illustrated in the drawing, it is preferable to provide its smaller dis-

charge end 29 with a thicker tip member than its receiving end, as the yarn tends to cause greater wear on the yarn tube discharge tip.

The disk-like elements 26 and 27 may each have a thickness within a range of about 0.005 inch to about 0.080 inch. The elements 26 and 27 also preferably have a width and length, or diameter, greater than the external diameter of the corresponding end of the tubular member 25.

10 In a yarn guide construction as shown in Figure VIII, the external diameter of the smaller end of the tubular member 25 and the corresponding end of the finished tube 11 may range from about 0.030 inch to about 0.10 inch depending on the gauge of the knitting machine and the yarn to be fed. The external diameter of the larger end of the tubular member 25 and the corresponding end of the finished tube 11 may range from about 0.062 inch to about 0.066 inch depending on the gauge of the knitting machine.

If it is desirable to provide a reversible yarn guide tube, so that it may be inverted in the yarn carrier and present either end as a yarn discharge tip, it would be preferable to have both disk-like members 26 and 27 of the same thickness. For a reversible yarn guide tube, it would also be desirable to eliminate the taper in the tubular member 25 and provide the latter in the form of a cylinder having uniform internal and external diameters throughout.

The disk-like members 26 and 27 are preferably integrally united or fused to the ends of the tubular member 25, as by welding. A preferred method and apparatus for this welding operation is disclosed in my co-pending application Serial No. 263,737, dated March 23, 1939, now Patent No. 2,218,977. After the welding operation, the welded assembly will appear as illustrated in Figure V of the drawing. A suitable instrument, such as a rotary drill 35, is now used to perforate the disk-like member 26 as more or less diagrammatically illustrated in Figure VI. This drill 35 is preferably of such character that it will form an opening in alignment with the interior of the tubular member 25 and of substantially the same internal diameter as the end 28 thereof. The drill 35 is then removed, and a smaller tool or drill 36 is inserted through the perforated disk-like element 26 and the tubular member 25 for the purpose of drilling or perforating the disk-like member 27. This drill 36 preferably has an overall diameter corresponding substantially to the internal diameter of the end 29 of the tubular member 25, so that the inner side wall of the end 29 will serve to guide and position the drill 36 in perforating the disk-like member 27. The disk 27 might be perforated by drilling from the exterior to the interior surface thereof in the same manner as described with respect to disk-like member 26. Experience shows, however, that the drilling operation as illustrated in Figure VII of the accompanying drawing is preferable and secures greater accuracy in aligning the opening in the disk-like element 27 with the interior of the tubular member 25.

Following the cutting or drilling operations, the outer or peripheral edges of the disk-like members 26 or 27 are preferably so ground or otherwise shaped that they will provide flush surfaces with the adjacent portions of the outer wall of the tubular member 25.

When the yarn guide tube has received the form of Figure VIII, the tip 27 (which has been formed from the disk-like element 27 of Figures III to VII) may be heat treated in any desirable

manner to further improve its wear resisting properties. For example, it may be connected to two electrodes of an electrical circuit and subjected to electrical resistance heating. That is the resistance of the tip 27 to the passage of current between the two electrodes results in the tip 27 being heated. By controlling the current conditions of the electrical circuit, the tip 27 will have its temperature raised to the desired degree. While the tip is still at a high temperature, it is removed from the electrodes and placed in a quenching bath to complete the treatment.

It is preferable that a portion of the tubular member 25 be tapered, as at 24, so that the lower or discharge end 29 thereof will have a smaller external diameter than the other end 28. This proportioning or shape secures certain desirable advantages. The yarn receiving end is formed of sufficient internal diameter to facilitate insertion of a yarn end. The upper tube end also provides 10 larger surface area for engagement with the socket jaws 15 and 16.

The illustrated proportioning and shape for the yarn guide 11 offers further advantages if the guide 11 is to be used on knitting machines for 25 so-called ringless knitting operations. It is the usual practice in such operations on straight knitting machines to employ a number of yarn carriers in the knitting of a single hosiery blank. These yarn carriers are so operated that their 30 external yarn laying tips travel in closely spaced parallel paths and frequently pass each other during knitting operations. The possibility of the tips colliding as they pass each other is minimized by the present construction in which the yarn guide tube 35 11 has a tapered portion 24 and a tip 27 (Figures I, II and VIII) of relatively small overall diameter.

The tubular member 25 is also preferably of 40 substantially cylindrical shape between the portion 24 and the discharge end 29 to steady the drill 36 as it perforates the disk-like element 27.

In lieu of separately welding a disk-like element to each yarn guide tubular member 25, the method illustrated in Figure IX may be followed. 45 This figure illustrates a method in which a plurality of tubular members 40 are welded to a strip or plate-like element 41. The strip or plate 41 may then be appropriately cut into sections so that each of the tubular members 40 will be provided with a separate tip forming piece. Yarn 50 guide tubes may then be formed and completed in accordance with the method previously described. The perforations for the individual tips may be provided either before or after the strip or plate 41 is cut or separated into sections. The strip or plate-like member 41 may be formed of 55 the same material as the disk-like members 26 and 27. The tubular members 40 may be formed in the same manner as the above described tubular members 25.

The foregoing is illustrative, and it will be understood that this invention includes all modifications and embodiments coming within the scope of the appended claims.

I claim:

1. The method of making yarn guide tubes for knitting machines comprising the steps of integrally uniting a blank of wear resisting material to one end of a tubular member, and forming an opening in said blank in alignment with the interior of said member to provide the same with an apertured yarn guide tip.

2. The method of making yarn guide tubes comprising the steps of integrally uniting, by 75

welding, a blank to one end of a tubular member in the form of a helical coil spring, and cutting an opening in said blank in alignment with the interior of said member to provide the same with an apertured yarn guide tip.

3. The method of making yarn guide tubes comprising the steps of integrally uniting, by welding, a disk-like blank to one end edge of a tubular member, cutting an opening in said blank in alignment with and of substantially the same size as the opening at the adjacent end of said member, and shaping the peripheral edge of said disk blank so as to conform in shape with the exterior of the adjacent end of the tubular member.

4. The method of making yarn guide tubes comprising the steps of integrally uniting disk-like blanks to the opposite ends of a tubular member, and forming openings in said blanks in alignment with the interior of said member to provide the ends of same with apertured yarn guide tips.

5. The method of making yarn guide tubes comprising the steps of integrally uniting disk-like elements to the opposite ends of a tubular member, forming openings in said elements in alignment with the interior of said member to provide the ends of same with apertured yarn guide tips, and shaping the peripheral edge of each of said elements to make the same conform in shape and size with the exterior of the adjacent portion of said tubular member.

6. The method of making yarn guide tubes comprising the steps of integrally uniting disk-like blanks to the opposite ends of a tubular member, forming openings in said blanks in alignment with the interior of said member to provide the ends of same with apertured yarn guide tips, shaping the peripheral edge of each of said blanks to make the same conform in shape and size with the exterior of the adjacent portion of said tubular member, and heat treating at least one of said tips to improve its wear resisting character.

7. The method of making yarn guide tubes comprising the steps of integrally uniting disk-like blanks to the opposite ends of a tubular member, forming an opening in one of said disk-like blanks by drilling from the exterior surface to the interior surface thereof, said opening being formed in alignment with the interior of said member, and forming an opening in the other of said disk-like members by drilling from the interior surface thereof to the exterior surface thereof.

8. The method of making yarn guide tubes comprising the steps of integrally uniting disk-like blanks to the opposite ends of the tubular member in the form of a helical coil spring, forming an opening in one of said disk-like blanks by drilling from the exterior surface to the interior surface thereof, said opening being formed in alignment with the interior of said member, forming an opening in the other of said disk-like blanks by drilling from the interior surface thereof to the exterior surface thereof, and removing outer edge portions of said disk-like blanks to make the same conform substantially with the exterior of the adjacent portions of the tubular member.

9. The method of making yarn guide tubes comprising the steps of providing a tubular member with substantially uniform wall thickness throughout and a tapering portion intermediate its ends, whereby the tubular member will have

its end portions of different external diameters, integrally uniting disk-like blanks to the opposite ends of said tubular member, forming an opening in the disk-like blank secured to the larger end of said tubular member, passing a tool through said opening and through the hollow interior of said tubular member and cutting an opening in the blank at the smaller end of said tubular member by means of said tool, said tool being of substantially the same size as said smaller end of the tubular member and being guided thereby in said cutting operation.

10. In a method of making yarn guide tubes, the steps comprising integrally uniting one end of each of a plurality of tubular members to a metallic plate or strip, and forming openings in said strip or plate in alignment with the interiors of said tubular members.

11. A method of making yarn guide tubes as recited in claim 10, wherein said strip or plate, after the formation of said openings, is separated into sections to provide each of said tubular members with a tip portion formed from said strip or plate.

12. The method of making yarn guide tubes comprising the steps of providing the opposite ends of a tubular member with disk-like elements, said elements being integrally united to said tubular member and being formed with openings in alignment with the interior of said member to provide the ends of same with apertured yarn guide tips, and shaping the peripheral edge of each of said elements to make the same conform in shape and size with the exterior of the adjacent portions of said tubular member.

13. A method of making yarn guide tubes for knitting machines, which method comprises the steps of integrally uniting, as by welding, a disk-like element to one end of a tubular member, and cutting an opening in said element in alignment with the interior of said tubular member to pro-

vide the same with an apertured yarn guide tip.

14. A method of providing a tip for a yarn guide tube to be used in a knitting machine, said method comprising the steps of integrally uniting a blank of wear resisting material to an end of a tubular member, and forming an aperture in said blank and in alignment with the interior of said tubular member by means of a tool inserted in said tubular member from the opposite end thereof, said tool being of substantially the same size as the bore of said tubular member adjacent said blank and being guided by the interior wall of said member in said aperture forming operation.

15. A method of making yarn guide tubes for knitting machines, which method comprises the steps of integrally uniting, as by welding, a disc-like element to one end of a tubular member, said element being of a metal substantially more resistant to wear than said tubular member, shaping said element to form the same into an apertured tip for the tubular member, and heat treating said tip to improve its wear resisting properties.

16. The method of making yarn guide tubes for use in straight knitting machines having yarn carrier arms each adapted to support a yarn guide tube and to reciprocate for laying yarn passing through the tube, said method comprising the steps of integrally uniting, as by welding, a disc-like blank of wear resisting material to one end of a tubular member of resilient construction, forming an opening in said blank in alignment with and of substantially the same size as the opening in the adjacent end of said tubular member, and shaping the blank so as to conform the blank to the exterior of said adjacent end of said tubular member.

AUGUST L. WEISBECKER.
